UNITED STATES PATENT OFFICE.

CHRISTIAN A. MARSCHEL, OF ST. LOUIS, MISSOURI, ASSIGNOR TO UNDERWOOD TYPE-WRITER COMPANY, OF NEW YORK, N. Y., A CORPORATION OF DELAWARE.

TYPEWRITING MACHINE.

Application filed March 30, 1920. Serial No. 369,850.

To all whom it may concern:

Be it known that I, CHRISTIAN A. MARSCHEL, a citizen of the United States, residing in the city of St. Louis and State of Missouri, have invented certain new and useful Improvements in Typewriting Machines, of which the following is a specification.

This invention relates to typewriting machines, and is herein disclosed as applied to an Underwood standard typewriting machine of the continuous billing or so-called fan-fold type, one form of which is disclosed in the patent to Wernery & Smith, No. 1,132,055, dated March 16, 1915.

In such machines, a plurality of plies of superposed webs, either fan-folded or not, are drawn over a rearward extension of the usual typewriter carriage, and pass beneath the platen, being threaded through carbon-paper-holding devices which are supported on the extension.

In such machines, the platen is displaceable to enable webs passed beneath it to be drawn forward substantially straight beneath the platen when the platen is in its displaced position, so that the webs may be gaged against a leading-edge gage and the carbons or carbon-sheets may be withdrawn by moving their supporting devices rearwardly along the extension. Such machines also usually include a knife located adjacent the printing line, but somewhat above it, the relationship of the carbon-sheets and the knife being such that after the webs have been gaged, and the supporting devices pushed rearwardly, the carbon-sheets lie behind the cutting edge of the knife, thus enabling the webs to be severed without interfering with the carbon-sheets.

Such machines are often used for simultaneously making copies of bills, statements, way-bills, bills of lading, dray-bills, etc. It is often desired, in making out such simultaneous copies, to have all the entries and extensions appear upon the bill, while only the heading, or only the heading and certain other entries, should appear on certain of the other copies.

According to the present invention, the carbon-paper-supporting devices, which usually form a single carriage or carrier, are divided, being made into two carriages or

carriers which may be separately moved, thus enabling one set of carbon-sheets to be withdrawn by one of the carbon-paper-carriages after the work-sheet has been partly typed, while the other carbon-paper-carriage is left undisturbed, thus permitting the carbon-sheets on the last-named carriage to reproduce the whole of the matter typed upon the outer sheet. The two carbon-paper-carriages may run upon the usual single set of rails, and each carriage may have associated therewith an independently adjustable stop for arresting it. Each of the carbon-paper-carriages may have its own handle for pushing it rearwardly, and where both carriages run upon the same rails, the rearward pushing of the forward carriage may push the rearward carriage rearwardly. Owing to the friction of the carbon-sheets upon the webs, the stop for arresting the forward carriage when moved rearwardly serves also to arrest the rearward carriage. When, however, the rearward carriage is separately moved rearwardly, its own stop may arrest it, at any desired position, thus taking off the mind of the typist any need of carefully positioning the rearward carriage.

Other features and advantages will hereinafter appear.

In the accompanying drawings,

Figure 1 is a fragmentary sectional side view of a typewriting machine of the class described, showing the present invention as applied thereto.

Figure 2 is a plan view of the two carriages and some adjacent parts.

Figure 3 is a sectional front view of the rear portion of the rear carriage, showing the stops and their mounting.

Figure 4 is a diagrammatic side view similar to Figure 1, but showing the position of parts after a heading on a form or section of the web has been written, and before the rear carriage has been moved rearwardly to withdraw its carbon-sheet beyond the rear end of the form of which the heading has been typed.

Figure 5 is a view similar to Figure 4, but showing the rear carriage moved rearwardly to carry its carbon-sheet behind the printing line.

Figure 6 is a view similar to Figure 5, but showing the position of the parts after

the bill or other work-sheet has been fully typed.

Figure 7 is a view similar to Figure 6, but showing the webs gaged against the leading-edge gage, and the carbon-paper-carriages pushed rearwardly to bring the carbon-sheets behind the knife preparatory to severing the webs.

In machines of the general type of the Wernery & Smith patent described above, webs 10, 11, 12 and 13, which are usually fan-folded, are drawn forwardly over the rear cross-bar 14 of an extension 15 of the typewriter carriage 16, passing beneath the platen 17, and up in front, past the printing point at the type-bar diagrammatically shown at 18, to a front paper-table 19.

The webs 10, 11, 12 and 13 have threaded between them carbon-sheets 20, 21 and 22, the first sheet 20 being supported upon a rear carbon-paper-carriage 23, and the carbon-sheets 21 and 22 being supported upon a front carbon-paper-carriage 24. These carbon-paper-carriages may, in many respects, resemble the carbon-paper-carriage of said patent, or the carriages of the machines now in use, in which each carriage comprises a body 25 having successively higher steps or bases 26 thereon, upon which carbon-paper clip-bars 27 are adapted to be detachably held fast by pins 28. The bases 26 of the rear carriage 23 are successively higher than the highest step 26 of the front carriage 24. The carriages 23 and 24 are shown as provided with rolls 29 which run upon the edges of rails 30, which form part of the extension 15, and are united by the cross-bar 14.

When the parts are in the Figure 1 position, the carbon-sheets all extend slightly above the printing line at 18, and the typist may write the heading or other desired matter upon a form on the outer sheet or web 13 by actuating the type-bars 18 through the usual keys, not shown. After each line is written, the typist actuates the usual line-space lever 31, which is effective on the line-space wheel 32 to rotate the platen 17 by means of the usual gears 33 and 34. After all the heading has been typed and it is desired to type on the rest of the form matter which shall appear only upon the two outer carbon copies, the typist seizes the webs 10, 11, 12 and 13, which have now reached the Figure 4 position, and, while holding them against the front paper-table 19, actuates the usual finger-piece 35 to free the swing-frame 36 from the usual catch 37, and swings the swing-frame 36 forwardly, lifting the platen 17 to the Figure 5 position. This straightens out the webs and enables the typist to push rearwardly, to the Figure 5 position, the rear carbon-paper-carriage 23 by pushing upon its handle 38 which extends forwardly to about the usual position of such

handles. It should be understood that the extent of such rearward movement is sufficient to withdraw the forward end of the carbon-sheet 20 to the rear of the lower end of the form being typed, and is substantially the same as the length of a form. Then the typist throws the swing-frame 36 rearwardly, so that it catches beneath the catch 37, and the typist continues to type upon the outer sheet and the two outer carbon-sheets. During this latter typing, the carbon-sheet 20, which is attached to the carbon-paper-carriage 23, is fed forwardly with the webs and the carbon-sheets 21 and 22 until the carbon-paper-carriages 23 and 24 reach their Figure 6 positions.

When the typist has finished all the typing to be done upon the form now being typed, so that the parts have reached the Figure 6 position, the typist again actuates the finger-piece 35 to release the catch 37, and swings the swing-frame 36 upwardly, and gages the leading ends of the webs against the usual adjustable leading-edge gage 39, which is adjustably mounted upon the usual extension 40 of the front paper-table. This may drag the front carbon-paper-carriage forwardly until the front end thereof strikes some part of the main typewriter carriage 16, and the typist, continuing the pulling upon the webs, pulls the rear carbon-paper-carriage or carbon-carrier 23 forward until the webs are gaged. Consequently, when the front carbon-paper-carriage 24 is pushed rearwardly by its handle 41 the whole length of one form in the usual manner, the two carriages come together before the front carbon-paper-carriage 24 strikes the adjustable stop 42, positioned in accordance with the length of the forms on the webs 10, 11, 12 and 13. The forward ends of the carbon-sheets are thus restored to their proper alignment which is maintained during the movement of the carbon-paper-carriage 24 to its Figure 7 position.

In order to enable the rear carbon-paper-carriage 23 to pass the stop 42, said stop is in the form of a hook having a flat top 43 adapted to overlie the rail 30, and having a hooked end 44, which embraces the rod 45 forming the stiffener for the rail 30. For adjusting the stop 42, there is provided a thumb set-screw 46 passing through it and adapted to bear against the rod 45, so that the flat top 43 is drawn down against the rail 30. To enable the carriage 24 to be arrested by this stop, said carriage is provided with a lug 47 on the bottom of its body 25, which lies beneath the body and above the adjacent rail 30.

In order to relieve the mind of the typist of having to observe the distance to which the rear carbon-paper-carriage 23 should be pushed by its handle 38 in bringing it to the Figure 5 position, there is provided a

stop 48, which is shown as adjustable along the left-hand rail of Figure 3, and which is adapted to be held in position along that rail by a thumb-screw 49. The stop 48 may 5 project to any desired extent above its adjacent rail 30, and may comprise legs 50, which extend beneath the edges of the rail 30, and are adapted to catch that rail and hold the stop in position upon the rail. The body 51 10 of the stop projects far enough above the rail to be struck by the rear end of the body 25 of the carbon-paper-carriage 23.

When the typist has finished the typing of the forms and has gaged the forms, as 15 shown in Figure 7, and drawn the swing-frame 36 back to the Figure 1 position, it is customary to sever the webs 10, 11, 12 and 13 by drawing them against the usual knife 52, which is somewhat above the printing line, although adjacent it. The stop 42 is so positioned relatively to this knife that when the carriages are brought to rest with the stop 42 effective, the carbon-sheets 20, 21 and 22 occupy the Figure 1 position, so 25 that the webs may be detached by drawing them against the knife 52 to sever them without severing the carbon-sheets. This leaves the webs and carbon-sheets positioned as in Figure 1, ready for typing the next 30 form.

The machine described is not limited in use to the particular mode of operation hereinbefore set forth. For example, one fan-fold web may be interleaved with the 35 carbons of the carbon-paper-carriage 23 and another fan-fold web may be interleaved with the carbons of the carbon-paper-carriage 24, and either of these webs may be typed upon to the exclusion of the other by 40 simply withdrawing the end of the web which is to be idle with its interleaved carbons from around the platen and laying it back upon its carbon-paper-carriage. With this arrangement the two webs may also be 45 typed upon together, when desired, by feeding them to the platen in superposed relation.

Variations may be resorted to within the scope of the invention, and portions of the 50 improvements may be used without others.

Having thus described my invention, I claim:

1. In a typewriting machine, the combination with a typewriter carriage comprising a platen, of a carbon-paper-carriage reciprocable upon the typewriter carriage, a second carbon-paper-carriage behind the first and movable rearwardly independently thereof, and a handle for the first carbon-paper-carriage adapted to move it rearwardly to move the second carbon-paper-carriage.

2. In a typewriting machine, the combination with a typewriter carriage comprising a platen, of a rearward extension of said

carriage comprising rails, two carbon-paper-carriages running upon said rails, one behind the other, a separate handle for each carbon-paper-carriage, and a separately adjustable stop for each carbon-paper-carriage. 70

3. In a typewriting machine, the combination with a typewriter carriage, of a platen displaceable in said carriage to permit superposed webs to be drawn forward substantially straight beneath it, and supporting means for carbon-sheets adapted to withdraw them rearwardly between the webs when the webs are thus straightened, said supporting means comprising provisions for withdrawing some of said carbon-sheets independently of the others. 80

4. In a typewriting machine, the combination with a typewriter carriage, of a platen displaceable in said carriage to permit superposed webs to be drawn forward substantially straight beneath it, a knife at the front of the platen adapted to sever the typed webs, a rearward extension of the carriage, a carbon-paper-carriage running on said extension and adapted to withdraw carbon-sheets supported thereon from between certain plies of the webs, a second carbon-paper-carriage also running on said extension and adapted to withdraw other carbon-sheets supported thereon from between other plies of the webs, said second carbon-paper-carriage adapted to move the first carbon-paper-carriage with it in one direction, a stop for the second carbon-paper-carriage adapted to arrest it when moving rearwardly so as to bring all the carbon-sheets behind the knife, and a separate stop adapted to arrest the first carbon-paper-carriage at a point still further back when independently moved rearwardly. 95

5. In a typewriting machine, the combination with a typewriter carriage, of a platen displaceable in said carriage to permit superposed webs to be drawn forward substantially straight beneath it, a knife at the front of the platen adapted to sever the typed webs, a rearward extension of the carriage comprising a pair of rails, two carbon-paper-carriages running on said rails, one behind the other, and adapted to withdraw carbon-sheets supported between different plies of the webs, a knife near the printing line for severing the webs, a stop for the front carbon-paper-carriage adapted to arrest it when pushed rearwardly to bring the ends of all the carbon-sheets behind the knife, and an independently settable stop for the rearward carbon-paper-carriage adapted to arrest it at a different point. 110

6. In a typewriting machine, the combination with a typewriter carriage, of a platen displaceable in said carriage to permit superposed webs to be drawn forward substantially straight beneath it, a knife at the front of the platen adapted to sever the 125

typed webs, a rearward extension of the carriage comprising a pair of rails, two carbon-paper-carriages running on said rails, one behind the other, and adapted to withdraw carbon-sheets supported between different plies of the webs, a knife near the printing line for severing the webs, a stop adjustable along one rail adapted to arrest one carbon-paper-carriage, and a separately 5 adjustable stop adapted to arrest the other carbon-paper-carriage, one of said stops so placed as to arrest its carriage with its carbons just behind the knife.

7. In a typewriting machine, the combination with a typewriter carriage, of a platen displaceable in said carriage to permit superposed webs to be drawn forward substantially straight beneath it, a knife at the front of the platen adapted to sever the 10 typed webs, a rearward extension of the carriage, a carbon-paper-carriage running upon said extension, a second carbon-paper-carriage also running upon said extension, a handle for the first carbon-paper-carriage 15 for moving it rearwardly independently of the second, a handle for the second carbon-paper-carriage adjacent the first handle, the arrangement of parts being such that pushing the second handle moves both carriages 20 rearwardly, and independently adjustable stops for both carriages.

8. In a typewriting machine, the combination with a typewriter carriage comprising a platen, of a rearward extension of said carriage comprising rails, two carbon-paper-carriages running upon said rails, one behind the other, a separate handle for each carbon-paper-carriage, a separately adjustable stop for each carbon-paper-carriage, 25 clip-bars successively higher upon the front carbon-paper-carriage, and still higher clip-bars also successively higher upon the rearward carbon-paper-carriage.

9. In a typewriting machine, the combination with a typewriter carriage comprising a platen, of a rearward extension of said carriage comprising rails, two carbon-paper-carriages running upon said rails, one behind the other, a separate handle for each carbon-paper-carriage, a separately adjustable stop for each carbon-paper-carriage, a stop for the front carbon-paper-carriage below the rail level, and adapted to allow the rear carbon-paper-carriage to clear it, and a 30 stop for the rear carbon-paper-carriage above the rail level.

10. In a typewriting machine, the combination with a platen, of a carbon-paper-carriage adapted to support a carbon-sheet covering a form to be typed while around the platen, a second carbon-paper-carriage also adapted to support a carbon-sheet to cover the same form on another work-sheet, a stop 35 for positioning both carbon-paper-carriages

at the beginning of writing a form, and a stop for repositioning the second carbon-paper-carriage to bring its carbon-sheet clear of the form after the form has been partly filled out.

11. In a typewriting machine, in combination, a platen, a carriage in which said platen is mounted, and carbon-controlling means including means mounted for operation to shift to an ineffective position one of a plurality of carbons interleaved between a plurality of work-sheets so as to be guided to the same field of the platen, and means for at the same time retaining another of said carbons in effective relation with the work-sheets.

12. In a typewriting machine, in combination, a platen around which are fed a plurality of superposed form-webs and interleaved carbon-sheets retractible from a completely typed section of the webs to the next section to be typed, a carriage in which said platen is mounted, and carbon-sheet-controlling means including a carbon-carrier on said carriage and attached to the rear end of one of said carbon-sheets and a second carbon-carrier on said carriage to the rear of the first carbon-carrier attached to another of said carbon-sheets and engaging the first carbon-carrier when the forward ends of the carbon-sheets attached to the two carbon-carriers are in alignment, the second carbon-carrier being shiftable rearwardly to retract its carbon-sheet to prevent copying therethrough during typing on the portion of the form on which typing is being effected, the first carbon-carrier being shiftable into engagement with the rearwardly positioned second carbon-carrier to restore the alignment between the forward edges of the carbon-sheets attached to the two carbon-carriers.

13. In a typewriting machine, in combination, type-bars, type-bar-supporting means to cause the type-bars to be guided to a single printing point, a platen, means for effecting a relative letter-space movement between the platen and the type-bar-supporting means, carbon-controlling means including means for shifting one of a plurality of carbons, interleaved between work-sheets on the platen, relatively to the other carbons and to the original work-sheet to render the shifted carbon ineffective for copying while holding the other carbons still effective, and means operable to re-align all of said carbons.

14. In a typewriting machine, in combination, a traveling carriage, a platen mounted in said carriage, and a plurality of independently reciprocable carbon-carriers on said carriage to deliver carbons to the same field of the platen.

15. In a typewriting machine, in combination, a traveling carriage, a platen mounted

in said carriage, a plurality of reciprocable carbon-carriers on said carriage to deliver carbons to the same field of the platen, and means to limit the movement of each of said 5 carbon-carriers.

16. In a typewriting machine, in combination, a traveling carriage, a platen mounted in said carriage, and two reciprocable carbon-carriers on said carriage, the first carrier, if in advanced position, being movable by a rearward movement of the second carrier.

17. In a typewriting machine, in combination, a traveling carriage, a platen mounted in said carriage, two reciprocable carbon-carriers on said carriage, said carbon-carriers being so related that one may be shifted rearwardly without the other, but shifting of the last-mentioned carrier rearwardly 20 will cause a corresponding movement of the other carrier if in advanced position, and a stop to limit the rearward movement of the second-mentioned carbon-carrier, but ineffective relative to the first-mentioned carbon-carrier.

18. In a typewriting machine, in combination, a carriage, a platen mounted therein, feeding means to co-operate with said platen to feed a plurality of work-sheets with carbon-sheets interleaved therebetween, means to release said work-sheets from said platen and feeding means to permit the work-sheets to be substantially straightened beneath the platen, and carbon-sheet-controlling means 30 for retracting all of said carbon-sheets and including means for retracting one of said carbon-sheets independently of the other carbon-sheets.

19. In a typewriting machine, in combination, a carriage, a platen mounted in said carriage, feeding means to co-operate with said platen to permit superposed webs with carbons interleaved therebetween to be advanced by the platen, a knife at the front 40 of the platen for use in severing the typed webs, a rearward extension of the carriage, a carbon-carrier running on said extension and connected with certain of said carbons to draw the same rearwardly, a second carbon-carrier also mounted on said extension to withdraw other carbons, provisions on 45 said carbon-carriers whereby the second carbon-carrier in its movement to the rear will move the first carbon-carrier therewith, a stop for the second carbon-carrier to arrest it when the carbons attached thereto are brought behind the knife, a separate stop to arrest the first carbon-carrier at points still further back when moved independently of the second carbon-carrier, and means to release the pressure between the platen and said feeding means and to permit the webs to be straightened so that the carbons may be drawn therefrom.

20. In a typewriting machine, in combination, a traveling carriage, a platen mounted in said carriage, feeding means to co-operate with said platen to feed a plurality of webs and interleaved carbons, means to release the webs from the platen and the feeding means 65 and to permit the webs to be straightened, and a plurality of carbon-carriers to direct the carbons to the same field of the platen and to selectively retract the corresponding carbons when the webs are straightened. 70 75

21. In a typewriting machine, in combination, a traveling carriage, a platen mounted in said carriage, and means to retract a plurality of carbons interleaved between a plurality of webs on the platen comprising a reciprocable carbon-carrier for retracting certain of said carbons attached thereto at their rear ends and means for independently retracting the remainder of said carbons. 80

22. In a typewriting machine, in combination, a traveling carriage, a line-feeding platen in said carriage around which work-sheets and interleaved carbons may be fed, and reciprocatory independent holders guided upon said carriage for delivering sets 85 of carbons to the same field of the platen, one of said holders movable to position for rendering its carbons ineffective independently of the carbons of the other holder. 90

23. In a typewriting machine, a plurality 95 of carbon-sheets mounted for movement toward and from the same field of the platen and interleaved with work-webs, means mounted for operation to shift part of said carbon-sheets along the work-webs with which they are arranged to co-operate, and means for, at the same time, holding another part of said carbon-sheets stationary with relation to the work-webs with which they co-operate. 100 105

24. In a continuous billing typewriting machine for typing on an outside ply of a multiple-ply work-web having registering printed forms thereon duplicating on a second ply of the web all of the matter typed on the outside ply and duplicating on a third 110 ply the matter typed on the upper portion only of the form on the outside ply, in combination, a platen, carbon-holding means, a plurality of carbons held by the holding means and co-operating, respectively, with the second and third plies of web, and carbon-controlling means arranged for shifting the carbon co-operating with the third ply 115 to uncover the lower portion of the form on the third ply when the portion of the typed matter which it is desired to duplicate on the third ply has been completed, and for at the same time maintaining the carbon 120 that prints upon the second ply in position to duplicate on the lower portion of the form on that ply the matter typed on the lower portion of the form on the outside ply. 125

25. In a typewriting machine, in combination, a traveling carriage, a line-spacing platen mounted in said carriage, carbon-carriers to deliver carbons to the same field of the platen, said carriage having means for guiding said carbon-carriers in back and forth movements, and a forwardly-extend-

ing handle upon each of said carbon-carriers to move it back and forth independently of the other.
